UNITED STATES PATENT OFFICE.

FREDRIC C. WEIR, OF CINCINNATI, OHIO.

CABLE OR RAILWAY CROSSING.

SPECIFICATION forming part of Letters Patent No. 398,206, dated February 19, 1889.

Application filed May 24, 1888. Serial No. 274,974. (No model.)

To all whom it may concern:

Be it known that I, FREDRIC C. WEIR, of Cincinnati, in the county of Hamilton and State of Ohio, have invented certain new and useful Improvements in Cable or Railway Crossings, of which the following is a specification.

The object of my invention is to provide a street-railway rail that can be readily and firmly attached to a cable railway, so as to form a protecting-guard crossing, the features of which will be fully set forth in the description of the accompanying drawings, making a part of this specification, in which—

15 Figure 1 is a top plan view of Fig. 2. Fig. 2 is a side elevation showing the tram-rail connected to a slot-rail and a street-railway rail. Fig. 3 is a central vertical section of my improvement united to a slot-rail. Fig. 4 is 20 a detail view of my improved rail in cross-section.

I represents a railway-rail provided with the flange-base 2 and tramway 3 and the guard 4, as shown in cross-section, Fig. 3. In order to 25 provide a strong support for the crossing, the rail 1 is provided with ears 5 6, cast on with said rails of a shape to fit the webs of the slot-ted rails and the girder-rails, to which they are respectively connected by means of bolts 7 30 and 8. In order to make the rail strong in cross-section, I make bosses 9, through which pass vertical bolts 10, to secure said rails to

the girder-support 11, which is preferably made of the form shown in an application of even date herewith, filed by F. C. Weir and 35 N. O. Goldsmith, Serial No. 274,912. The rear end of said rail 1 is provided with a guard, 12, so as to prevent derailment at its junction with the ordinary girder-rail, 13, as shown in Fig. 1.

In order to connect the tram-rail 1 to the street-rails, I provide two ears, 6 6, as shown in Fig. 4, which fit the web of said street-rail and are connected thereto, as shown in Fig. 2, by bolts 8.

11 represents the girder or support of said rail 1. Rail 1 is made of two sections, the inner ends of which are bolted to the slot-rails.

Having described my invention, what I 50 claim is—

1. The crossing-rail 1, provided with base 2, tramway 3, flange 4, and the ears 5, substantially as herein set forth.
2. The crossing-rail 1, provided with bosses 9, ears 5 and 6, with the tramway 3, and guard 4, substantially as herein specified.

In testimony whereof I have hereunto set my hand.

FREDRIC C. WEIR.
